US00D572189S

(12) **United States Design Patent**
Sarnowsky et al.

(10) **Patent No.:** **US D572,189 S**
(45) **Date of Patent:** **** Jul. 1, 2008**

(54) **WIRELESS CHARGING DEVICE**

(75) Inventors: **Melvin J. Sarnowsky**, Livonia, MI (US); **Robert B. Bucciarelli**, Plymouth, MI (US); **Royce D. Channey**, Ann Arbor, MI (US)

(73) Assignee: **Visteon Global Technologies, Inc.**, Van Buren Township, MI (US)

(**) Term: **14 Years**

(21) Appl. No.: **29/295,422**

(22) Filed: **Sep. 28, 2007**

(51) **LOC (8) Cl.** **13-02**

(52) **U.S. Cl.** **D13/108**

CLAIM

The ornamental design for the wireless charging device, as shown and described.

DESCRIPTION

FIG. 1 is a perspective view of the wireless charging device; FIG. 2 is a left elevational view of the wireless charging device, the right elevational view being a mirror image thereof;

FIG. 3 is a front elevational view of the wireless charging device;

FIG. 4 is a rear elevational view of the wireless charging device;

FIG. 5 is a top plan view of the wireless charging device; and, FIG. 6 is a bottom plan view of the wireless charging device.
